UNITED STATES PATENT OFFICE

94,853

DESIGN FOR A TABLE LAMP

Oscar A. Reinhold, Chicago, Ill.

Application January 11, 1935, Serial No. 54,811

Term of patent 3½ years

To all whom it may concern:

Be it known that I, Oscar A. Reinhold, a citizen of the United States, residing at Chicago, in the county of Cook and State of Illinois, have invented a new, original, and ornamental Design for Table Lamps, of which the following is a specification, reference being had to the accompanying drawing, forming part thereof.

In the drawing:

Figure 1 is a side elevation of my new design for a lamp, and,

I claim:

The ornamental design for a table lamp, as shown and described.

OSCAR A. REINHOLD.
